UNITED STATES PATENT OFFICE.

ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

STARTER FOR INTERNAL-COMBUSTION ENGINES.

1,301,478.

Specification of Letters Patent. Patented Apr. 22, 1919.

Application filed February 20, 1915. Serial No. 9,717.

To all whom it may concern:

Be it known that I, ALBERT HENRY MIDGLEY, a subject of the King of Great Britain and Ireland, and residing at Warple Way, 5 Acton Vale, in the county of Middlesex, England, have invented certain new and useful Improvements in and Relating to Starters for Internal-Combustion Engines, of which the following is a specification.

10 This invention relates to an improved electric starter for internal combustion engines such as is used for the driving of motor cars and other purposes and of the kind in which an electric motor is used in combination with a helical gear which has a longitudinally displaceable member and is interposed between the electric motor and the engine to be started in order to effect and maintain the coupling during the starting 15 operation and automatically to effect the uncoupling.

In starters of this kind, as hitherto proposed, in addition to the means for starting the electric motor, separate means have been 20 employed for effecting the engagement or the initial engagement of the driving gear.

The present invention consists in effecting the initial engagement of the driving gear by a short longitudinal movement of 25 the shaft of the electric motor, which longitudinal movement is produced by energizing the magnetic field of the motor and then automatically completing the said engagement by the sliding movement of one member 30 of a helical gear on said shaft, the automatic disengagement being effected by the same means operating in a reverse direction. In the starter constructed according to the present invention, the shaft to which 35 the armature of the electric motor is secured has a small longitudinal movement relatively to the axis of the magnetic field, which movement is just sufficient for bringing the teeth of the members to be coupled together 40 into initial engagement with one another.

It is known to effect the coupling between the gear members of an electric starter for internal combustion engines by securing one 45 of the gear members to a shaft to which is attached a motor armature arranged to be drawn into the magnetic field by the magnetic action of the latter. However, in this form of starter as hitherto constructed the whole of the coupling is effected by the longitudinal movement of the armature rela-

tively to the axis of the field, which movement must necessarily be comparatively long as it has to cover the distance between the gear members when they are out of engagement with each other and the full width 60 of the movable gear member. The electric starter constructed according to the present invention has the advantage as compared with this form of starter that the longitudinal movement of the armature is reduced to 65 the small distance between the gear members when they are out of engagement with each other and consequently the energy required for the excitation of the motor at the beginning of the starting operation is also 70 reduced and the size of the motor is decreased.

The invention is illustrated by way of example in the accompanying drawing.

Referring to the drawing, the armature 75 shaft *a* of an electric motor *b* carries a pinion *c* which is provided with spiral teeth and which is slidably mounted on the shaft *a*, the latter being for this purpose castellated as shown at *d* or provided with a key. 80 The electric motor *b* is preferably of the type in which when the motor receives the current from the battery the armature, together with the shaft *a* and the spiral pinion *c* mounted thereon, are moved longitudinally because of the attraction between the armature and the field magnet, thereby 85 bringing the spiral teeth of the pinion *c* in engagement with the spiral teeth provided on the other member *e* of the gear, the latter member being preferably formed on the flywheel *f* of the engine. Immediately upon the initial engagement of the two members *c* and *e* of the spiral gear, the spiral pinion *c* on the armature shaft *a* is caused to slide on 90 the latter because of the rotation of the armature, whereby the two members *c* and *e* are caused to come into full engagement with each other. The engine having thus been started the tendency thereof to drive 95 the motor *b* causes the spiral gears *c* and *e* to come out of engagement with each other, in which position they are kept by means of a spring *g* interposed between the pinion *c* and a member *h* taking up the axial thrust 100 and adapted to rotate on a ball bearing *i*.

The connections of the electric motor with the battery may be as follows:—The armature *p* and the excitation windings *q* provided on the poles of the electric motor *b* 110

are connected with a split battery l_1 , l_2 through the intermediary of the two arms m n of a switch as follows:—When the two arms m n are in the positions illustrated on the drawing, the motor is entirely disconnected from the battery and is therefore inoperative; by shifting the arms to the positions in which they make contact with the stationary contacts m_1 and n_1 respectively, 5 the excitation windings q are connected across the larger portion l_2 of the battery and at the same time the armature p is connected to the smaller portion l_1 of the battery, the circuit being; battery l_1 , arm n , contact n_1 , a resistance o , brush k_2 , commutator j , armature p , commutator j , brush k_1 , stationary contact m_1 , arm m , and back to the battery l_1 . When the arms are in this position a large current is sent through the excitation windings q and a small current is sent through the armature p whereby the armature p is strongly attracted within the magnetic field under slow rotation. By further shifting the arms m n into such positions that m is disconnected from m_1 and n makes contact with the stationary contact n_2 , the armature p is connected in series with the excitation windings q and with the whole of the battery l_2 , l_1 , the circuit being battery l_2 , l_1 , arm n , contact n_2 , brush k_2 , commutator j , armature p , commutator j , brush k_1 , excitation windings q , and back to the battery. When the circuit is thus completed, 30 the speed of rotation of the armature is increased until the engine is started.

Having now described my invention, what I claim as new and desire to secure by Letters Patent is:—

1. An electric starter for internal combustion engines for automatically effecting the coupling of the engine and starting motor, comprising in combination with the engine shaft an electric motor having a longitudinally displaceable armature shaft, a 40 helical gear having two coöperating mem-

bers, one of which constitutes a driving member and is mounted on the longitudinally displaceable armature shaft in such a manner as to be capable of both rotating therewith and of sliding thereon in a longitudinal direction, and means for simultaneously rotating the armature shaft and longitudinally displacing it, together with the said driving member mounted thereon, to a position of initial coupling between the two 50 shafts through the intermediary of the driving member, whereby the further rotation of the armature shaft, after the said initial coupling, causes the one member of the helical gear to shift longitudinally relatively to the other member thereof, thereby completing the coupling between the two shafts, as 60 set forth.

2. An electric starter for internal combustion engines for automatically effecting 65 the coupling of the engine and starting motor, comprising in combination with the engine shaft an electric motor having a longitudinally displaceable armature shaft, keyways provided on a portion on the armature 70 shaft, and a pinion slidably mounted on the said keywayed portion and provided with helical teeth, a wheel mounted on the engine shaft and provided with helical teeth which are cut to correspond to those 75 on the said pinion so as to constitute together a helical gear, and means for simultaneously rotating the armature shaft and longitudinally displacing it, together with the pinion mounted thereon, to a position of 80 initial coupling between the said pinion and wheel, as and for the purpose set forth.

In testimony whereof I have signed my name to this specification in the presence of two subscribing witnesses.

ALBERT HENRY MIDGLEY.
